UNITED STATES PATENT OFFICE

119,584

DESIGN FOR A DECK OF PLAYING CARDS

Edward N. Bessling, Washington, D. C.

Application July 6, 1939, Serial No. 85,856

Term of patent 14 years

To whom it may concern:

Be it known that I, Edward N. Bessling, a citizen of the United States and resident of the city of Washington, District of Columbia, have invented a new, original, and ornamental Design for a Deck of Playing Cards, of which the following is a specification, reference being had to the accompanying drawing forming a part thereof, which drawing is a face view of one of each different variety of card in the complete deck of cards showing my new design. The deck consists of seventy-two cards composed of four complete sets of the eighteen cards shown in the drawing.

I claim:

The ornamental design for a deck of playing cards, as shown and described.

EDWARD N. BESSLING.
